UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

STALL CONSTRUCTION.

1,101,169.

Specification of Letters Patent. Patented June 23, 1914.

Application filed October 19, 1912. Serial No. 726,642.

To all whom it may concern:

Be it known that I, HENRY L. FERRIS, a citizen of the United States, residing at Harvard, in the county of McHenry and State 5 of Illinois, have invented a new and useful Improvement in Stall Construction, of which the following is a specification.

My invention relates to certain new and useful improvements in stall-construction, 10 and is fully described and explained in the specification and shown in the accompanying drawings, in which:—

Figure 1 is an elevation of the front of the stall embodying my improved construction; Fig. 2 is a section on the line 2 of Fig. 1; Fig. 3 is a section on the line 3 of Fig. 1; Fig. 4 is a view whose direction is indicated by the arrow 4 in Fig. 1, but with the adjacent part of the stall-frame re- 20 moved; Fig. 5 is an enlarged detail elevation, with certain parts in section, of the intermediate portion of the stall-front; Fig. 6 is a section on the line 6 of Fig. 1; Fig. 7 is a section on the line 7 of Fig. 8, and Fig. 8 25 is an elevation, similar to Fig. 1, of a modified form of the construction.

Referring to the form of construction shown in Figs. 1 to 6, inclusive, 9 are upright posts set in the curb at the front of 30 the stall. Mounted on these posts are pivot-pins 10 formed integral with clamping members 11 which grasp the posts. Inasmuch as the stalls are ordinarily arranged in series, each clamping member has upon it a pivot- 35 pin 10, there being thus provided upon each post 9 pivot-pins extending in opposite directions, although, of course, at the end of the series one of the pivot-pins will be omitted. 12 and 13 are the lower and upper 40 halves of the stall-front frame, each being U-shaped in form, the two halves being pivoted upon the pivot-pins by a hinged joint, the form of which is shown in Fig. 5, from which it will be seen that the members 45 12 and 13 of the frame have in their ends hinge-members 14 which are journaled upon the pivot-pins 10, or the reduced extensions thereof, and are held in place thereon by cotter pins. Within the stall-front frame is 50 a stanchion 15, swiveled at the top in an ordinary manner and at the bottom attached to a chain 16, the ends of which are spaced apart and attached to the lower portion of the corresponding member of the stall-front 55 frame. By this construction the stanchion

is yieldingly supported at its bottom and is thus given a certain capacity for longitudinal movement at its lower end in the stall-front frame, but without any capacity for substantial lateral movement, and in addition, provision is thus made for the upper and lower ends of the stall-front frame approaching, or receding from each other slightly, when adjusted, as will hereinafter be-described.

For the purpose of adjusting the stanchion back and forth to accommodate animals of different lengths, each of the vertical posts 9 carries at its upper end a plate 17 provided with a plurality of holes for adjustment, the two plates 17 being preferably arranged in pairs on opposite sides of the posts 9 and clamped together thereon as illustrated. Each of the plates 17 carries an adjustable fork 18 engaging the upper portion of the stall-front frame. By adjusting this fork longitudinally of its plate, the upper half of the stall-front frame can be swung backward or forward around its pivot and held in any desired position. To accomplish a corresponding movement at the bottom, a vertical plate 19 with a longitudinally-spaced series of perforations is provided on the curb (Figs. 1 and 6). Centrally pivoted to the lower portion of the stall-front frame is a link 20 bifurcated at its end to saddle the plate 19 and having perforations through which a bolt can be passed, whereby, by engaging said bolt with any of the perforations in the plate 19, the lower end of the stall-front frame can be adjusted to correspond with the upper.

Referring now to the form of construction shown in Fig. 8, the arrangement is in main similar to that already described. 95 There is this difference however, the vertical posts 9 are continued higher and are connected at their upper ends by a cross-bar 20^a upon which is a vertical plate 21, similar to the plate 19 at the bottom, and the upper member 13 of the stall front has a pivoted bifurcated link 22 (Figs. 7 and 8), similar in construction and operation to that at the bottom in the form of construction already described. In this construction, therefore, the plates 17 and forks 18 are omitted, and an adjusting and locking mechanism similar to that used in the other form at the bottom is provided instead. By this construction, as well as the other, the upper and lower 100 105 110

parts of the stall-front frame can be adjusted, so that the stanchion will approach or recede from the gutter, which is customarily provided at the rear end of the stall, so as to accommodate the stall to animals of various sizes.

I realize that considerable variation is possible in the details of the present construction and, by describing the same in detail, I do not intend to limit myself thereto, except as pointed out in the following claims, in which it is my intention to claim all the novelty inherent in the construction as broadly as is permitted by the state of the art.

What I claim as new and desire to secure by Letters Patent is:—

1. In a stall construction, a stall-front frame consisting of upper and lower parts pivoted on horizontal transverse pivots whereby their extremities can be swung longitudinally of the stall, means to adjustably fix the position of said parts, and a stanchion between the ends of said frame parts, for the purpose set forth.

2. In a stall construction, a stall-front frame consisting of upper and lower parts pivoted on horizontal transverse pivots whereby their extremities can be swung longitudinally of the stall, means to adjust-

ably fix the position of said frame parts, a stanchion between the ends of said frame parts, and yielding means between the stanchion and one part of said frame, for the purpose set forth.

35

3. In a stall construction, a stall-front frame consisting of upper and lower parts pivoted on horizontal transverse pivots whereby their extremities can be swung longitudinally, a fork to grip one part of the frame, means to support said fork adjustably, and a stanchion between the ends of said frame parts, for the purpose set forth.

4. In a stall construction, a stall-front frame consisting of upper and lower parts pivoted on horizontal transverse pivots whereby their extremities can be swung longitudinally of the stall, a link on a part of said frame, means to engage the end thereof adjustably, and a stanchion between the ends of the front-frame parts, for the purpose set forth.

In testimony whereof I have hereunto affixed my hand this 15th day of October, 1912.

HENRY L. FERRIS.
